UNITED STATES PATENT OFFICE

LOUIS CHARLES BREETZ, OF YOUNGSTOWN, OHIO

LAMP RECEPTACLE

Application filed June 16, 1930. Serial No. 461,301.

This invention relates to improvements in electrical fixtures, and more especially to that class of fixtures ordinarily denominated weatherproof lamp receptacles, such as are usually employed in industrial plants and for similar outdoor or relatively exposed uses as distinguished from the somewhat more decorative receptacles employed in homes, office buildings and the like in which protection from rain or other water or undue moisture is afforded by the building itself.

Weatherproof receptacles of the class described have heretofore ordinarily been provided with a molded shell of bakelite, porcelain or similar insulating or non-conductive material having insulated conductors permanently molded therein to provide means for interconnecting the receptacle with a source of current, the conductors extending outwardly from the opposite end of the receptacle from that into which the lamp is adapted to be screwed. The conductors usually consist of short pieces of insulated wire thus requiring for connection with the current source that they be spliced at points a few inches from the receptacle to other wires ultimately extending thereto. In making the splice the wires are scraped free of insulation for a short distance from their ends and then respectively twisted to the similarly scraped ends of line wires, and each splice is individually taped with insulating tape, after which both splices are taped together, thus making a rather bulky and unsightly swelling in the line at a short distance from the receptacle. When such a receptacle is thus connected to an extension cord and then moved about, as by a workman carrying a light from place to place in the performance of his duties, the splice, which is generally the weakest place in the line, is subjected to constant bending in different directions as a result of which the wires comprised therein soon become broken or exposed with consequent arcing across, short circuiting and danger of injury to the person using the light. In fact, many workmen have been seriously injured and sometimes killed in industrial plants and the like by shocks received by

coming into contact with wires exposed in this manner.

To obviate this condition various sorts of handles have been proposed, but none of them, so far as I am aware, are entirely satisfactory as they are bulky and expensive, particularly when designed to afford protection to the spliced joint.

A principal object of my invention, therefore, is to provide a receptacle of the class to which I have referred to which may be easily secured cheap and readily obtainable means adapted to form a convenient handle and also to enclose the lead wires, whereby the latter are protected from undue wear or abuse, the danger of their breaking at the splice or otherwise greatly diminished, and the possibility of inadvertent contact with exposed conductors by a workman employing the receptacle in connection with an extension cord substantially avoided.

Other purposes, objects and advantages of my invention are hereafter more specifically mentioned or will be apparent from the following description of a preferred embodiment thereof and of certain typical circumstances in which it may be advantageously employed, in connection with which reference will be had to the accompanying drawings.

In the said drawings, Fig. 1 is a side elevation of my improved weatherproof receptacle; Fig. 2 is a side elevation of the same showing its preferred manner of employment in connection with a flexible extension cord; Fig. 3 is a view corresponding to Fig. 2 but with certain parts shown in central vertical section, and Fig. 4 is a side elevation of the receptacle showing how it may be employed in association with rigid conduit fittings of an ordinary type, parts of which are shown in vertical section. Like characters are used to designate like parts in the several figures.

As shown in the drawings, the receptacle shell 1, which may be formed of "Bakelite", porcelain, hard rubber or any other moisture resistant insulating material, is provided with a boss 2, extending rearwardly from that end of the receptacle opposite that designed to receive the lamp and adapted for

the passage therethrough of insulated wires 3 such as are ordinarily provided for connecting a weatherproof receptacle to the line, the boss 2 being provided with external screw threads 4 which may desirably be one-half inch pipe threads. For convenience and economy in manufacture and to avoid a joint between the boss and the shell of the receptacle, I prefer to form the shell and the boss as an integral molded unit. The wires 3, as well as the usual metallic threaded sleeve and other parts associated therewith through which connection between the electric light and wires is effected in the customary way, may be positioned in the mold at the time the receptacle is made, and are thereafter securely maintained in proper position within the boss by the "Bakelite" or other material employed, and a weather and moisture proof joint is thereby made between the boss and the insulating covering of the wires. Additionally, I prefer to form the threads 4 simultaneously with the molding operation, and it will be understood that the mold is therefore preferably provided with the proper internal threads to effect this result.

The boss is adapted to receive means operative to serve as a handle for the receptacle or to form a fixed support therefor depending upon the particular use to which the receptacle is to be put. Thus when the receptacle is to be used in connection with a flexible cord, as shown in Figs. 2 and 3, I may provide, to form a convenient handle, a piece of ordinary hose 5, which may desirably be externally corrugated as shown, of proper diameter to receive the boss 2, and of suitable length.

As will be best understood from reference to Fig. 3, when assembling the parts under these conditions, the hose is first slipped over and along the flexible extension cord 6 far enough to expose the end of the latter and the wires 3 then spliced to the conductors 7 thereof in the usual manner, tape 8 being employed to individually protect the spliced joints which need not be thereafter taped together. The hose is then slipped down over the splice and screwed onto the end of the boss 2, an operation which may be very easily performed as the threads 4 readily cut suitable complementary threads in the inner wall of the hose, thus firmly securing these parts together.

When thus assembled, it is apparent that the hose 5 serves as a handle for the receptacle and, although flexible to a limited extent, nevertheless protects the splice from undue bending, wear or other factors tending either to break the conductors at this point or expose their surfaces whereby the dangers attendant upon such breakage or exposure are entirely avoided. Moreover, the joint formed between the hose and the receptacle is water and damp proof which is of material advan-

tage when the receptacle is to be employed in mines or other wet or damp places, for of course the hose may be extended as far as is desirable along the cord and water and moisture thus effectually excluded from the vicinity of the splice.

The hose, which may be of the ordinary garden or other readily procurable variety, thus forms a cheap and effective handle for the receptacle and serves to fully protect the user from contact with the wires therein enclosed under all conditions and prevents any possibility of electrical shock even though one of them for any reason should become broken or exposed through its covering of insulating material.

My improved receptacle may also be employed in stationary or fixed installations, for example by connecting it through the medium of a pipe coupling 10 with a rigid conduit 11 in which are disposed line wires 12 as shown in Fig. 4, the coupling being interposed between and screwed upon the boss and the end of the conduit, or may be utilized in numerous other ways in various sorts of electrical installations as will be readily apparent to those familiar therewith.

While I have herein shown and described a preferred form of the invention with some particularly, I do not thereby desire or intend to confine myself specifically thereto as the shell of the receptacle may be of any desired form and the kind and size of the threads or other fastening upon the boss may be varied as desired, and/or other modifications and changes made in the details of design and construction without departing from the spirit and scope of the invention as defined in the appended claims.

Having thus described my invention, I claim and desire to protect by Letters Patent of the United States:

1. A weatherproof lamp receptacle comprising a molded hollow shell adapted to receive the base of an electric light and having integrally molded therewith a rearwardly extending boss of smaller diameter than the shell adapted for interconnection with means for supporting the receptacle, and a pair of wires extending through and molded into the boss for connecting the receptacle to a current source.

2. A weatherproof lamp receptacle comprising a molded shell adapted to receive the base of an electric light and having integrally molded therewith a rearwardly extending boss adapted for interconnection with means for supporting the receptacle, and wires leading through and molded into the boss for connecting the receptacle to a current source.

3. A weatherproof lamp receptacle comprising a molded shell adapted to receive at one end the base of an electric light and having an integral externally threaded boss extending from its other end, and wires leading

through and sealed in said boss for connecting the receptacle to a current source.

4. A weatherproof lamp receptacle comprising a molded shell adapted to receive the base of an electric light and having a rearwardly extending boss adapted for interconnection with means for supporting the receptacle, and wires leading through and sealed in the boss for connecting the receptacle to a current source.

10 In witness whereof I have hereunto set my hand this 13 day of June, 1930.

LOUIS CHARLES BREETZ.
